CARRIER FOR COILED RULER

John Evans, Scotch Plains, N.J.

Application August 22, 1958, Serial No. 52,344

Term of patent 14 years

(Cl. D52—1)

Fig. 1 is a front elevational view of a carrier for coiled ruler;

Fig. 2 is a view looking downwardly on the carrier;

Fig. 3 is a side view;

Fig. 4 is a back view taken from a direction opposite of Fig. 1; and

Fig. 5 is a view looking upwardly toward Fig. 3 and showing the bottom of the carrier.

The coiled ruler shown in broken lines in Fig. 1 is for illustrative purposes only.

I claim:

The ornamental design for a carrier for coiled ruler, substantially as shown and described.
